UNITED STATES PATENT OFFICE

147,495

DESIGN FOR A BUOYANT SOAP DISH

Donna L. Fenlason, Scarsdale, N. Y.

Application March 6, 1946, Serial No. 127,169

Term of patent 3½ years

(Cl. D4—3)

To all whom it may concern:

Be it known that I, Donna L. Fenlason, a citizen of the United States, residing at Scarsdale, in the county of Westchester and State of New York, have invented a new, original, and ornamental Design for a Buoyant Soap Dish, of which the following is a specification, reference being had to the accompanying drawing, forming part thereof, in which the figure is a perspective view of a buoyant soap dish showing my new design.

I claim:

The ornamental design for a buoyant soap dish, as shown.

DONNA L. FENLASON.
